UNITED STATES PATENT OFFICE

2,409,642

LASTING MACHINE

Charles A. Robinson, Salem, Mass., assignor to
United Shoe Machinery Corporation, Flemington, N. J., a corporation of New Jersey

Original application December 20, 1944, Serial No.
568,964. Divided and this application August
10, 1945, Serial No. 610,111

5 Claims. (Cl. 12—14)

1

This invention relates to lasting machines, the present application being a division of a copending application for Letters Patent for improvements in Machines for use in the manufacture of shoes, Serial No. 568,964, filed on December 20, 1944. The machine shown in that copending application, in which the present invention is herein illustrated as embodied, is a power-operated toe-lasting machine constructed in many respects as disclosed in United States Letters Patent No. 2,160,846, granted on June 6, 1939, on an application of F. C. Eastman's and A. F. Pym's. In common with that prior disclosure the machine is provided with wipers which in the course of a cycle of power operations of the machine are moved heightwise of the last to perform what is commonly known as an upwiping operation on the toe end of the upper and in automatically determined time relation to that movement are advanced lengthwise of the last and are closed inwardly widthwise of the last into positions to render them thus effective on the upper, such closing action on the wipers terminating after the beginning of their movement heightwise of the last. An object of the present invention is to provide improved means for operating the wipers, and especially to render more uniform their operations on shoes of different styles. While the invention is herein illustrated as embodied in a modification of the wiper-operating means shown in the above-mentioned Letters Patent, it is to be understood that it is not thus limited in its applicability.

With the above-stated general object in view, the invention provides means for varying, as may be desirable for shoes of different styles, the time in the operation of the machine when the closing action on the wipers to bring them into positions for the upwiping operation is terminated. The construction shown includes a cam and connections leading therefrom to the wipers for partially closing them, and another cam which by relative movement of parts of those connections supplements the wiper-closing action of the first cam and is adjustable to vary the time of its action on the wipers. Accordingly, the time when the wipers by their closing movements arrive in positions for effective upwiping action on the upper may be advanced or delayed relatively to the time of their movement heightwise of the last, depending upon the style of shoe to be lasted, so that if the shoe has a comparatively low or receding toe the wipers will not be closed so far inwardly as to necessitate that they be thereafter wedged apart substantial distances by the shoe

2

in the upwiping operation with danger of applying excessive pressure to the upper.

The invention will now be more particularly described with reference to the accompanying drawings and thereafter pointed out in the claims.

5 In the drawings,

Fig. 1 is a view in right-hand side elevation of a portion of the machine in which the invention is shown as embodied;

10 Fig. 2 is a plan view on an enlarged scale of the wipers and of parts closely associated therewith; and

Fig. 3 is a view partly in right-hand side elevation and partly in section, also on an enlarged 15 scale, showing portions of the wiper-operating means.

As more fully disclosed in the above-mentioned copending application, the machine in which the invention is herein shown as embodied is provided with a device 2 for positioning a welt shoe in proper relation to the toe-lasting means by engagement with the bottom face of the toe end of the insole and with the inner face of the lip of the insole at the end and the sides of the toe upon presentation of the shoe to the machine, the position of a shoe thus determined being indicated by broken lines in Fig. 3. Shortly after the starting of the cycle of power operations of the machine the shoe is clamped against the 20 shoe-positioning device 2 by a toe rest 4 which is moved upwardly into clamping position. As part of the lasting means the machine has a pair of wipers 6 which are advanced lengthwise of the last and are closed inwardly widthwise of the last to embrace the upper closely about the toe end of the last and in automatically determined time relation to their advancing and closing movements are swung upwardly to wipe the upper heightwise of the last, after which they are further advanced and closed to wipe the marginal 25 portion of the upper inwardly over the feather and against the lip of the insole, the lip being supported against the inward pressure of the wipers by the shoe-positioning device 2. The 30 wipers are secured to wiper holders 8 which are supported on a wiper carrier 10 and are guided by the carrier for movements about an axis extending heightwise of the shoe substantially at the end of the toe to close the wipers inwardly 35 widthwise of the shoe. The wiper carrier is supported at its front end for movements to advance and retract the wipers lengthwise of the shoe on a pair of links 12 which are spaced apart widthwise of the shoe and are pivotally connected at 40 the upper ends to the carrier. At its rear end 45 the wiper carrier is supported for movements to advance and retract the wipers lengthwise of the shoe on a pair of links 12 which are spaced apart widthwise of the shoe and are pivotally connected at 50 the upper ends to the carrier. At its rear end 55 the wiper carrier is supported for movements to advance and retract the wipers lengthwise of the shoe on a pair of links 12 which are spaced apart widthwise of the shoe and are pivotally connected at the upper ends to the carrier. At its rear end

the wiper carrier is further supported on the upper end of a lever 14 which is pivotally mounted between its upper and lower ends on a fulcrum rod 16. The upper arm of the lever 14 is pivotally connected by a rod 18 to the wiper carrier and, in effect, serves as a link substantially parallel to the links 12. The links 12 are pivotally connected at their lower ends to arms 20, only one of which is visible in the drawings, these arms being fast on a rockshaft 22 mounted in bearings in the frame of the machine. Also fast on the rockshaft 22 is an arm 24 provided with a roll 26 which lies in a cam track 28 formed in one side of a cam member (not shown) fast on a cam shaft 30. Only a fragment of this cam track is herein shown by dotted lines, but it corresponds to the cam track 190 of the above-mentioned Letters Patent No. 2,160,846. Through this mechanism the wiper carrier 10 is swung upwardly about the rod 18 to cause the wipers to wipe the upper heightwise of the last and is later operated to increase the downward pressure of the wipers on the marginal portion of the upper over the insole. To advance and retract the wiper carrier and the wipers lengthwise of the shoe, the lever 14 is swung about the rod 18 by a cam track 32 formed in one side of a gear wheel 34 on the cam shaft 30, the lever carrying a roll 36 which lies in the cam track. It will be understood that when the wiper carrier is thus operated the links 12 swing idly about their pivotal connections with the arms 20. Through spring means not herein shown but fully disclosed in Letters Patent No. 2,160,846 provision is afforded for yield to prevent damage to the shoe or to the machine when the upstanding margin of the upper is pressed against the lip of the insole by the action of the lever 14 on the wiper carrier.

The wiper holders 8 are operated to close the wipers inwardly widthwise of the shoe through links 38 (Figs. 2 and 3) connected respectively to the different holders and both operated by a slide 40 mounted for movements lengthwise of the shoe on the wiper carrier 10. Associated with these links are comparatively light springs 42 through which the wipers are pressed yieldingly against the sides of the toe in the wiping of the upper heightwise of the last. As disclosed in Letters Patent No. 2,160,846, the yield of these springs is limited to render the slide 40 positive in its action on the wiper holders 8 when the upper is thereafter pressed inwardly by the wipers against the lip of the insole. Through spring mechanism 44, the construction of which need not be herein described in detail in view of the disclosure in the above-mentioned Letters Patent, the slide 40 is operated to close the wipers by a bell-crank lever 46 mounted to swing about a shaft 48 supported by the wiper carrier 10, this bell-crank lever being connected by a pair of links 50, only one of which is herein shown, to the spring mechanism. This spring mechanism is yieldable to prevent damage to the shoe or to the machine when the upper is pressed against the lip of the insole by the closing of the wipers. The bell-crank lever 46 is operated by a cam track 52 formed in one side of the gear wheel 34 and acting on a roll 54 carried by an arm 56 which is fast on a rockshaft 58 on the frame. Also fast on this rockshaft is an arm 60 connected to the bell-crank lever 46 by means presently to be described, so that when swinging movement in a counterclockwise direction (Fig. 3) is imparted to the arm 56, corresponding

movement is imparted to the bell-crank lever 46 to close the wipers in time relation to their advancing movement lengthwise of the shoe and when reverse movement is imparted to the arm 56 the wipers are opened. By the portion *a* of the cam track 52 closing movements are imparted to the wipers preparatory to the wiping of the upper heightwise of the last, and by the portion *b* of the cam track they are thereafter further closed to wipe the marginal portion of the upper inwardly over the insole, these movements being accompanied by corresponding bodily advancing movements of the wipers lengthwise of the shoe. The receding portion *c* of the cam track later serves partially to open the wipers simultaneously with partial retractive movements thereof lengthwise of the shoe; the downward pressure of the wipers on the upper having been somewhat relieved at that time by the action of the cam track 28 on the wiper carrier 10. Thereafter the portion *d* of the cam track 52 again closes the wipers simultaneously with a second advance thereof lengthwise of the shoe, in time relation to which movements they are again moved downwardly to increase their pressure on the upper, all in accordance generally with the disclosure of the above-mentioned Letters Patent.

It will be evident that if the closing movements of the wipers to bring their edges into positions for wiping the upper heightwise of the last take place, as heretofore, in an invariable time relation to their upwiping movements, the positions of the edges of the wipers when they first become effective on the upper may depend upon the style of the shoe. That is, in operating, for example, on a shoe having a comparatively high toe the wipers may not be closed inwardly to any substantial extent beyond the widest portion of the toe, while in operating on a shoe having a comparatively low or receding toe they may be closed more or less inwardly under the sides of the toe before they become effective on the upper. In the latter case the wipers are thereafter necessarily forced somewhat apart against the resistance of the springs 42 by the wedging action of the shoe thereon as they are moved farther upwardly. To avoid any possible danger of excessive pressure of the edges of the wipers on the upper under those conditions, the construction herein shown is such that the time when the closing action on the wipers to bring them into positions for wiping the upper heightwise of the last is terminated may be varied. To this end, the closing of the wipers to those positions is effected, not alone by the cam track 52, but by additional means which supplements the action of this cam track and the time of operation of which is adjustably variable. As shown in Fig. 3, the means connecting the wiper-closing bell-crank lever 46 to the arm 60 which operates it comprises a pair of toggle links 62 and 64 pivotally connected respectively to the bell-crank lever and to the arm and connected together by a pin 66. This pin is connected by a link 68 to an arm 70 which is fast on the previously mentioned shaft 48 on which the bell-crank lever 46 is loosely mounted, and also fast on this shaft is an arm 72 (Fig. 1) connected by a link 74 to the upper end of an arm 76 which is pivotally mounted at its lower end on a bracket 78 on the frame. Mounted on the arm 76 is a roll 80 arranged to be engaged by the periphery of a cam 82 which is secured on one side of another cam 84 with which the machine is provided, this cam being fast on the cam shaft 30. The cam 82 is thus adjustably secured to the cam 84

by screws 86 extending through slots 88 in the cam 82. A spring 90 connected to the arm 76 tends to swing the arm toward the left, as the parts are viewed in Fig. 1, and thereby tends to turn the shaft 48 in a clockwise direction, the roll 80 being initially spaced somewhat from the cam 82. A screw 92 (Fig. 3) which is threaded in an upwardly extending lug on the upper end of the link 64 and engages a lug on the side of the link 62 limits the turning of the shaft 48 under the influence of the spring 90 and adjustably determines the normal positions of the toggle links 62, 64 with the toggle broken toward the left as the parts are viewed in Fig. 3. In these positions the links provide an operating connection between the arm 60 and the bell-crank lever 46. At a time in the cycle of operations which may be varied by adjustment of the cam 82 about the axis of the cam shaft 30 in the manner permitted by its screw-and-slot connection with the cam 84 a rise 94 on the cam 82 engages the roll 80 and through the mechanism described straightens the toggle 62, 64, thereby imparting further closing movements to the wipers supplementary to the closing movements effected by the portion *a* of the cam track 52. In this manner the wipers are closed to positions for the effective wiping of the upper heightwise of the last. It will be understood that in operating on shoes having comparatively high toes the cam 82 will be so adjusted as to advance the time of the straightening of the toggle, and that in operating on shoes having comparatively low or receding toes the cam will be adjusted to delay the straightening of the toggle relatively to the movement of the wipers heightwise of the last, so that the wipers will not be closed inwardly under the sides of the toe in such manner as to cause them thereafter to be wedged apart to any substantial extent by the action of the shoe thereon. It will further be understood that adjustment of the screw 92 will serve to vary the initial positions of the wipers widthwise of the shoe and correspondingly to vary the amount of movement imparted to the wipers by the cam 82 by varying the position of the roll 80 relatively to the cam.

Since the manner of operation of the construction provided by the invention has been fully explained above, no further explanation thereof is necessary.

Having described the invention, what I claim as new and desire to secure by Letters Patent of the United States is:

1. In a lasting machine, wipers for engaging an upper about the toe end of a last, power-operated means for effecting relative movement of said wipers and the last to cause the wipers to wipe the upper heightwise of the last, and means for closing the wipers inwardly widthwise of the last in predetermined time relation to said relative movement to bring them into posi-

tions thus to act on the upper, said wiper-closing means being adjustable to terminate such closing action on the wipers at a variably predetermined time with respect to said relative movement.

5. 2. In a lasting machine, wipers for engaging an upper about the toe end of a last, power-operated means for effecting relative movement of said wipers and the last to cause the wipers to wipe the upper heightwise of the last, and means for closing the wipers inwardly widthwise of the last in predetermined time relation to said relative movement to bring them into positions thus to act on the upper, said wiper-closing means including a cam adjustable to terminate its closing action on the wipers at a variably predetermined time with respect to said relative movement.

20. 3. In a lasting machine, wipers for engaging an upper about the toe end of a last, power-operated means for effecting relative movement of said wipers and the last to cause the wipers to wipe the upper heightwise of the last, means for closing the wipers inwardly widthwise of the last in predetermined time relation to said relative movement to bring them into positions thus to act on the upper, said wiper-closing means including a cam for partially closing the wipers and another cam for further closing them, said other cam being adjustable to terminate its closing action on the wipers at a variably predetermined time with respect to said relative movement.

25. 4. In a lasting machine, wipers for engaging an upper about the toe end of a last, power-operated means for effecting relative movement of said wipers and the last to cause the wipers to wipe the upper heightwise of the last, a cam and connections leading therefrom to the wipers for closing them inwardly widthwise of the last toward positions for thus operating on the upper, and another cam for supplementing the wiper-closing action of said first-named cam by relative movement of parts of said connections, said other cam being adjustable to vary the time of its action on the wipers.

30. 5. In a lasting machine, wipers for engaging an upper about the toe end of a last, power-operated means for effecting relative movement of said wipers and the last to cause the wipers to wipe the upper heightwise of the last, a cam and connections leading therefrom to the wipers for closing them inwardly widthwise of the last toward positions for thus operating on the upper, said connections including a toggle bodily movable thus to act on the wipers, and another cam associated with said toggle for flexing it and for thereby supplementing the wiper-closing action of said first-named cam, said other cam being adjustable to vary the time of its action on the wipers.

CHARLES A. ROBINSON.
